UNITED STATES PATENT OFFICE.

ELMER F. BLISS, OF SCHENECTADY, NEW YORK, ASSIGNOR TO GENERAL ELECTRIC COMPANY, A CORPORATION OF NEW YORK.

SIGNALING IN FLUID SYSTEMS.

1,413,313.

Specification of Letters Patent. Patented Apr. 18, 1922.

Application filed February 14, 1917. Serial No. 148,684.

To all whom it may concern:

Be it known that I, ELMER F. BLISS, a citizen of the United States, residing at Schenectady, in the county of Schenectady, 5 State of New York, have invented certain new and useful Improvements in Signaling in Fluid Systems, of which the following is a specification.

This invention relates to a method of 10 transmitting signals in a compressed air or other fluid system and more especially to a method by which signals may be transmitted through the ordinary air brake pipes which connect the various cars of modern 15 railway trains. Objects of my invention are to provide a novel method and novel means of utilizing compressed fluid systems for the transmission of signals. Other objects 20 of my invention are to provide a method and means of transmitting signals through railway trains by means of the train pipes of the compressed air brake systems without inducing undesired action on the part of various apparatus of the brake system.

25 It is well understood that some system of signaling is often necessary or desirable between the different units of a railway train, especially where the train is long or a single train is propelled by two locomotives; unity of action by the two locomotives is of great advantage. I am aware that various means have been devised in the past for utilizing for signaling purposes one of the pipes of the compressed air brake system 30 of the train, but all such schemes have been based so far as I am aware, on the raising or lowering of the pressure throughout the whole system, as by pumping in more air on the one hand or by venting the system 35 to decrease the pressure on the other hand. In other words, the pressure throughout the whole system has been materially raised or lowered an appreciable value each time the receiving device is actuated.

40 My invention distinguishes from such prior practices in that I set up only pulsations of pressure change, such pulsations comprising local fluctuations in pressure, or pressure waves, which are transmitted 45 through the compressed-air system in accordance with any prearranged code or system of signals without either materially increasing the normal pressure throughout the system or materially lowering it, the effect 50 being analogous to the pulsating of the blood

in the arterial system of the human body. These pulsations are received by a device some part of which is arranged to be vibrated or otherwise operated by the pulsations, and the natural frequency of vibration or other operation of which is equal to the frequency of the pulsations. By "natural frequency," it will be understood, I refer to the frequency at which the part of the receiver will vibrate or otherwise 60 operate when free and once started. One advantage of this "tuning" is that although the individual pulsations at the receiver may be weak, they may be made to operate the receiver by utilizing the cumulative effect 65 of several pulsations for each signal or element of a signal.

In the accompanying drawings, Fig. 1 is a diagrammatic illustration of a simple form of automatic air brake system embodying my invention; Fig. 2 shows a train equipped with such a system and Figs. 3 and 4 diagrammatically illustrate two forms of mechanism for setting up the signaling 70 pulsations.

Referring first to Fig. 1 of the drawings: The usual train pipe of an automatic air-brake system for railway trains is shown at 1, the air pressure in this pipe being controlled for the purpose of operating the 85 brakes by means of the engineer's valve 2. The necessary air is supplied to the engineer's valve 2 from the main reservoir 3 which in turn is supplied by the motor-driven compressor 4. The triple valve 7 90 controls in the usual way the flow of air from the train pipe 1 to the auxiliary reservoir 5 and the admission of air to and its exhaust from the brake cylinder 6. The brake system illustrated is of a common 95 and well known type and is merely illustrative of any fluid system to which my invention may be applied, and hence requires no further description.

The features of the fluid system illustrated 100 which comprise my invention consists of a transmitting device or pulsator shown in outline at 8 in Figs. 1 and 2, and a receiving or indicating device 9. For certain forms of pulsator 8, a source of pressure 10, to provide air for the pulsator 8 under materially greater pressure than that of the train pipe 1 will be necessary; it may be given its pressure in any desired way. These features 105 may respectively assume any one of numer- 110

ous forms and those forms I have shown and later described are substantially only illustrative.

The receiving device illustrated at 9 is constructed on the principle of the ordinary steam or air gauge consisting of a sensitive Bourdon tube connected to a system of multiplying links and levers arranged to operate a hammer between two bells to give audible signals. A transmitting device or pulsator 8 requiring a source of pressure 10 is shown developed in Fig. 3. In this pulsator there is a valve 12 in the passage 13 between the pulsator source of pressure 10 and the train-pipe 1, and a valve 14 in an exhaust port 15 from the train pipe 1. These valves are interlocked and operated together, as by the stem 11 which is normally pressed to the right by the spring 16 so that the valve 12 normally closes passage 13, while the exhaust port 15 is normally open around the valve 14. A handle 17, pivoted at 18, is adapted to move the stem 11 to the left to open the passage 13 and close the exhaust port 15. A valve 19 which normally closes the exhaust port 15 but opens automatically when the pressure in the train-pipe exceeds a predetermined value, tends to limit the pressure in the train pipe 1. A valve 20, also under the control of the pressure in the train pipe 1, closes the passage 13 when the train pipe pressure exceeds a predetermined value. The valves 19 and 20 may or may not be enclosed in the pulsator case 8. When the operator desires to transmit a signal, he moves handle 17 to the right and then substantially immediately returns it to the position illustrated in Fig. 3; this momentarily opens the valve 12, the opening being of sufficient size and being sufficiently quickly opened and closed to admit an impulse or pressure wave to the train-pipe from the reservoir or source 10 without admitting sufficient air to the pipe 1 to materially raise the whole pressure of this pipe. This impulse passes through the train-pipe and operates upon the indicating device 9, but creates such small differences in pressure and exists at any one point in the train-pipe for such a short period of time as to cause or result in no operation of the brake apparatus. A second and subsequent impulses may be passed later, it being understood that the valve 12 is to be held open only momentarily for each impulse. The valve 14, closing the exhaust port 15 while the impulse is being started in the train-pipe, prevents the escape of the impulse or wave of pressure at its inception by way of the exhaust port 15. On the other hand the exhaust port 15 and valve 19 provide for the prompt release of any excess pressure throughout the system which may be caused by the signaling. Were no means provided to prevent it, the operator might carelessly or otherwise hold the valve 12

open sufficiently long to materially raise the pressure throughout the train-pipe and thus immediately or ultimately, unpremeditatedly, operate some of the air-brake apparatus, for while the reducing valve 19 as 70 previously described would open automatically at a certain pressure, the valve 14, closed when the valve 12 is opened, would prevent the venting of the train-pipe to atmosphere thereat. In order to prevent any 75 such possibility, I have provided the valve 20 to operate automatically to close the passage 13 at a pressure about that required to operate valve 19.

The pulsator of Fig. 3 may be employed 80 to completely operate the indicator 9 with each opening of the valve 12 so that each opening of the valve 12 results in the transmission of a complete signal or an element or part of a complete signal. In such a 85 case, of course, the pressure wave or pulsation admitted by the single opening or closing of the valve 12 must be of sufficient amplitude to operate the indicator. However, the pulsator 8 may be operated, for example automatically, in such a way as to set up in the pipe 1 a plurality of pulsations or train of pressure waves for each signal or element of a complete signal, the frequency of the plurality of pulsations or waves of 90 the train being substantially equal to the natural frequency of the indicator. The waves of each series of pulsations in such a case may act cumulatively on the receiver to induce the signal or single element of a 95 100 signal. As above indicated, one advantage of this "tuning" and utilization of a plurality of pulsations for each element of a signal, is that the individual pulsations at the receiver may be relatively weak, and hence the indicator operated through a longer length of fluid column or operated by individually weaker pulsations at the pulsator.

Fig. 4 illustrates diagrammatically a pulsator particularly adapted for providing a plurality of pulsations or a train of waves for each element of a signal or each operation of the indicator. This pulsator comprises a cylinder 30 provided with a piston 31, fairly air-tight, movable therein. The interior of this cylinder 30 communicates at the face of the piston 31 with the train pipe 1. A motor 33 through suitable gears and links is adapted to rapidly reciprocate the 115 piston 31 within the cylinder 30. Such a pulsator may be readily arranged to provide a train of pressure waves within a train pipe 1 of a fairly constant frequency so long as the motor 33, which may be an electric 120 motor, drives the piston 31. To give a signal with such a pulsator, the motor 33 will be started and stopped for each simple signal or each element or part of a complete signal. It will be understood that pulsator 130

tions of any suitable frequency may be used, and that while a fairly low frequency will probably nearly always be required when each pulsation provides a complete 5 element or part of a signal, in order to avoid confusion, no such limitation is necessarily imposed on the frequency when a plurality of pulsations or train of pressure waves is employed for each element or part of a signal, and with suitable pulsators and indicators for each case the frequency may be anywhere within the range throughout which the fluid of the system is able to transmit distinct pulsations.

15 In accordance with the provisions of the patent statutes, I have described the principle of operation of my invention, together with the apparatus which I now consider to represent the best embodiment thereof; but

20 I desire to have it understood that the apparatus shown is only illustrative, and that the invention can be carried out by other means.

What I claim as new and desire to secure by Letters Patent of the United States, is:—

25 1. The method of transmitting signals in an air brake system comprising a train pipe carrying air under pressure, which consists in setting up within the train pipe a plurality of pulsations of a predetermined frequency without varying the amount of air

30

within the train pipe, and operating at a distant point directly by said pulsations a vibrating indicator whose natural frequency corresponds to the frequency of said pulsations.

35

2. The combination with a fluid system comprising a confined column of fluid, of controllable means for setting up a plurality of pulsations or trains of pressure waves of a predetermined frequency within the fluid 40 column, and a vibrating indicator operated directly by said pulsations and having a natural frequency substantially equal to the frequency of said pulsations.

3. The combination with a railway air 45 brake system comprising a train pipe carrying air under pressure, of controllable means connected to said train pipe for setting up a plurality of pulsations or trains of pressure waves of a predetermined frequency in 50 the air within the train pipe, and a vibrating indicator connected to said train pipe at a point remote from said first mentioned means, operated directly by said pulsations and having a natural frequency substantially 55 equal to the frequency of said pulsations.

In witness whereof, I have hereunto set my hand this 13th day of February 1917.

ELMER F. BLISS.
